UNITED STATES PATENT OFFICE.

MARC SOLON, OF TRENTON, NEW JERSEY, ASSIGNOR TO THE POTTERS EQUIPMENT COMPANY, (INC.), OF NEW YORK, N. Y., A CORPORATION OF NEW JERSEY.

DECORATING-KILN AND THE LIKE.

1,354,518.

Specification of Letters Patent.

Patented Oct. 5, 1920.

Application filed December 8, 1917. Serial No. 206,150.

To all whom it may concern:

Be it known that I, MARC SOLON, a subject of the King of Great Britain, and resident of Trenton, in the county of Mercer and State of New Jersey, have invented certain new and useful Improvements in Decorating-Kilns and the like, of which the following is a specification.

The object of my present invention is to provide an arrangement of heating flues for a decorating kiln or the like by which there will be secured economy in fuel, a uniform distribution of the heat, and saving of wear and tear. Another object of my invention is to provide an improved way of supporting the goods within the kiln. These features and others will be described in detail in connection with the accompanying drawings, and the novel features of the invention will then be pointed out in the appended claims.

A typical example of a kiln embodying my improvements is shown in said drawings, Figure 1 being a vertical section of the kiln, taken on line 1—1 of Fig. 2; Fig. 2 is a composite horizontal section, the parts to the left of the broken line being in section on line 2—2 of Fig. 1, and the parts to the right of said broken line being in section on line 2a—2a of Fig. 1; Figs. 3 and 4 are vertical sections taken on lines 3—3 and 4—4 respectively of Fig. 1, and Fig. 5 is a partial horizontal section on line 5—5 of Fig. 3.

The kiln illustrated is of substantially rectangular form in plan or horizontal section, being provided with a vertical front wall A, a vertical rear wall B, and side walls, the lower portions C, C' of which are vertical, while their upper portions are arched to form a crown portion C''. The front wall A is provided with a door D for the introduction and removal of the goods to be treated, and at the lower portion of one of the side walls, say C, I arrange a suitable number of furnaces E, of any appropriate construction. Owing to the improved arrangement of heating channels, described below, I am enabled to obtain the desired heating effect with a smaller number of furnaces than heretofore. Thus the two furnaces indicated in the drawing will heat efficiently a kiln of a size which would require four furnaces if constructed according to present practice.

The kiln is provided with a bottom F and also with a floor or false bottom G preferably made of tiles and located at a suitable distance above the bottom F so as to leave a space between them. Within the kiln, above the floor G and following the curvature of the side and top walls C, C', C'', is located an inner wall H, preferably made of interlocking tiles, and spaced from said side and top walls, said wall H extending from the front wall A to the rear wall B. Partitions J arranged in vertical planes, subdivide the space between the wall H and the walls C, C', C'' into arched flues K, and L, L'. One end of each flue K communicates with the adjacent furnace E, the particular construction shown having a group of three flues K and one flue L, L'. The other ends of the flues K communicate with a chamber M, formed below the floor G on one side of a longitudinal vertical partition N which extends from the front wall to the rear wall. On the other side of said longitudinal partition are located heating flues O hereinafter referred to. A transverse partition N' located beneath the floor G separates the chambers M and flues O belonging to different groups, there being one group for each furnace E. The lower end of each flue L communicates with the corresponding chamber M, and the upper end of said flue connects with a smoke flue P' in the chimney P, located at the crown of the kiln.

The upper end of the flue L' communicates with a smoke flue P'' in the chimney P, while the lower end of said flue L' is open to the flues O, disposed in sinuous fashion and formed by midfeathers of baffles R, in conjunction with the partitions N, N', side wall C, bottom F and floor G, said baffles extending up from the bottom to the floor. Each furnace E communicates with its group of flues O by means of an opening or channel S.

A transverse partition Q, located at the crown, between the walls C'', H, separates the flues L, L' of one group from the flues L, L' of the other group, and said partition may be extended into the chimney P as shown, to separate the flues P', P'' of one group from the flues P', P'' of the other group. Another partition Q' (Fig. 1) extends within the chimney P longitudinally of the kiln, and down to the upper surface

of the wall H, this longitudinal partition separating the flues P' from the flues P''.

In the central portion of the rear wall B I locate a heating flue T, having an opening T' at the crown of the kiln, to receive a portion of the combustion gases, diverted at that point from one of the flues K, and passing through the flue T, by way of an opening T'' at the lower end thereof, into the chamber M which is adjacent to said rear wall. This diverted portion of combustion gases therefore travels through a by-pass, the main path of the combustion gases from the furnaces E being in parallel through the flues K, first up along the side wall C, then across at the crown C'', and then down along the other side wall C', thus reaching the respective chambers M under the floor G, and traveling from each of said chambers through the respective flue L along the side wall C' to the smoke flue P'. Another portion of the combustion gases travels from each furnace E through the respective channel S into the flues O located under the floor G, and passes from said flues upwardly along the side wall C, through the flue L' to the smoke flue P''. It will be seen that in this manner I conduct heating gases around the kiln chamber at practically every side thereof, except the front, but this omission is not detrimental in practice, in fact, the suppression of the flue T in the rear wall B would not seriously reduce the efficiency of the operation.

In order to improve the heating effect, I prefer to give the flues K a cross section decreasing progressively from their inlets (near the furnace) to their outlets (at the chambers M), so that the same volume of combustion gases will come in contact with a progressively increasing wall surface as the temperature of the gases decreases. Thus the increased ratio of wall surface to gas volume secured for the relatively cooler gases will, as it were, bring a larger number of gas particles, per unit of time, into contact with the respective portions of the kiln walls, and a thorough utilization of the heat will be obtained. Another feature which I prefer to employ for the same purpose, consists in making the inner wall H of a thickness reduced gradually in the direction in which the combustion gases travel along said wall in the flues K. The conduction of heat through the wall H will therefore take place through progressively thinner wall portions as the temperature of the gases in the flues K decreases.

For convenience in construction, the flues L, L' are given the same shape, in cross section, as the adjacent portions of the flues K. Another feature of my invention consists in the manner of supporting the bats or like bases, containers, etc., which receive the goods under treatment. For this purpose,

I have shown posts U located on the floor G at points vertically above the midfeathers or baffles R, with I beams V carried by said posts and extending transversely to the direction of said baffles. These beams preferably have their upper surfaces in the same horizontal plane, and are adapted to support the iron bats W or the like carrying the ware. It will be seen that with this arrangement the weight of the ware is supported virtually by the baffles R, and the floor G is practically relieved of the function of sustaining the weight of the ware, so that a comparatively thin (tile) floor may be employed.

It will be understood that in the particular construction shown, the combustion gases travel within the kiln walls, as it were, or around the kiln chamber, that is to say, said gases do not enter the chamber containing the ware.

Various modifications may be made without departing from the nature of my invention as set forth in the appended claims.

I claim:

1. A kiln provided with walls and heating flues in opposite walls, said flues having a heat-supply connection and an outlet connection, and a by-pass heating flue located in one of the other walls and having its upper end connected with a point of the other flues relatively near the supply connection, and its lower end connected with said flues at a point relatively near the outlet connection.

2. A kiln having a floor with a space thereunder, a partition dividing said space into two separate chambers, a source of heat having a direct connection to one of said chambers, the kiln having side walls and a top wall and heating flues extending along said walls and connecting said source of heat with the other chamber under the floor, and outlet flues leading from the respective chambers.

3. A kiln having a floor with a space thereunder, a partition dividing said space into two separate chambers, baffles to form a tortuous path in one of said chambers, a source of heat having a direct connection to said baffle chamber, the kiln having side walls and a top wall, with heating flues extending along said walls and connecting said source of heat with the other chamber under the floor, both chambers having outlets for the escape of the heating medium.

4. A kiln having end walls, side walls, and a top wall, with heating flues extending along said side walls and top wall and connected with an outlet, and a by-pass heating flue located in one of said end walls and connected at one end with the upper portion of one of the side wall heating flues to receive its supply of heating medium therefrom, and at the other end with said outlet.

5. A kiln having a floor with a space thereunder, a partition dividing said space into two separate chambers, a source of heat having a direct connection to one of said chambers, the kiln having side walls and a top wall and heating flues extending along said walls and connecting said source of heat with the other chamber under the floor, the kiln also having end walls one of which 10 is provided with a heating flue having its upper end connected with one of the side wall heating flues and its lower end connected with the same chamber under the floor with which said side wall heating flues are 15 connected, both chambers having outlets for the escape of the heating medium.
6. A kiln having a floor with a space thereunder, a partition dividing said space into two separate chambers, baffles to form a tortuous path in one of said chambers, a 20 source of heat having a direct connection to said baffle chamber, the kiln having side walls, end walls, and a top wall, with heating flues extending along said side walls and top wall and connecting said source of heat 25 with the other chamber under the floor, a heating flue extending along one of said end walls and communicating at its upper end with one of said side wall heating flues and at its lower end with the same chamber under the floor with which said side wall heating flues are connected, and outlet flues extending from the respective chambers along the side walls of the kiln to the top wall 30 thereof.

MARC SOLON.
